UNITED STATES PATENT OFFICE

2,273,782

WASHER FEEDING DEVICE

Charles J. Irwin, Chicago, Ill., assignor to Illinois
Tool Works, Chicago, Ill., a corporation of Illi-
nois

Application October 3, 1940, Serial No. 359,542

15 Claims. (Cl. 10—169)

This invention relates to a machine or mechanism for assembling screws and washers, and more particularly to a means for feeding washers to an assembly point.

It is an object of this invention to provide for use in a screw and washer assembly mechanism or the like a washer feed device including a shiftable washer feed member or disc and means for preventing the washers from piling up or bunching on the feed member or disc.

It is a further object of the invention to provide a washer feed device having a shiftable washer feed member or disc and means to cause the washers to be properly seated in predetermined individual positions on the shiftable washer feed member or disc for conveyance to a predetermined point and to cause each of the washers to be positioned in a predetermined manner at said point.

More particularly it is an object of the invention to provide in combination with a recessed washer feed disc or shiftable member means to prevent the washers from jumping out of the recesses as the disc or shiftable member is operated.

The invention also contemplates the provision of means cooperating with a recessed washer feed disc or member to insure positioning of a single washer in each recess and its proper seating therein and to prevent interlocking of other washers with the washer so positioned or seated.

It is also an object of the invention to provide a washer feed device including a hopper receiving a mass of washers and a disc or shiftable member operating beneath the mass to receive washers therefrom, and means cooperating with the disc or member to insure the feeding of the received washers in individual succession into a predetermined position at a predetermined point.

Crown washers, i. e., washers having outwardly pressed central portions or "crowns," have a tendency to bunch up or stack while being fed to a much greater extent than flat washers, the washers in a stack having a tendency to roll on edge along the feeding surface and pile up against the hopper wall.

It is therefore an important object of applicant's invention to provide in a device for feeding countersunk washers, means tending to prevent the stacking of the washers, and acting if a stack is formed to separate the washers from the stack so that they may be properly fed.

It is also an object of this invention to devise a device for feeding internal tooth lock washers

from a mass in individual succession to a mechanism for assembling such washers with screws to produce unit assemblies of an internal tooth lock washer and a screw.

5 A further object of the invention is to provide a device or mechanism for feeding or conveying internal tooth lock washers, particularly such washers of the crown type, from a receptacle or hopper containing a random mass of such washers.

10 Other and further objects and advantages of the invention will be apparent from the following description, when taken in connection with the accompanying drawings, wherein certain preferred embodiments of the invention are illustrated and wherein:

Figure 1 is a fragmentary view in plan of a machine or mechanism embodying the invention;

Figure 2 is a fragmentary view in vertical section taken along the line 2—2 of Figure 1;

Figure 3 is a fragmentary view in vertical section taken along the line 3—3 of Figure 1;

Figure 4 is a view in elevation and partly in section of an assembled screw and lock washer unit manufactured by a machine or mechanism for which the device of the present invention is adapted;

Figure 5 is an enlarged fragmentary view in plan taken along the line 5—5 of Figure 3 and showing the construction of the washer feed disc;

Figure 6 is a fragmentary plan view of another portion of the washer feed disc;

35 Figure 7 is a fragmentary view in vertical section taken along the line 7—7 of Figure 6;

Figure 8 is a fragmentary view in vertical section taken along the line 8—8 of Figure 5;

Figure 9 is a fragmentary view in perspective of the washer feed disc;

Figures 10 and 11 are views similar to Figures 6 and 7 for illustrating certain features of the operation of the washer feed disc;

45 Figure 12 is a fragmentary plan view similar to Figure 5, but showing another form of washer feed disc;

Figure 13 is a fragmentary view in perspective of the washer feed disc of Figure 12;

Figure 15 is a fragmentary plan view similar to Figure 5, but showing another form of washer feed disc;

Figure 16 is a fragmentary plan view similar

to Figure 5, but showing still another form of washer feed disc.

As shown in Figures 1 to 3, screw elements or blanks 2 are fed to the assembly mechanism 4 along the inclined gravity feed chute 6 composed of spaced inclined guide bars 8 and 10. The screw elements or blanks may be supplied to the chute 6 by any suitable conventional mechanism or device as shown in Hanneman Patent No. 2,152,591, issued March 28, 1939.

From the assembly mechanism 4 the screw elements or blanks assembled with washers are conveyed by an inclined chute 12 composed of spaced bars 14 and 16. By the chute 12 these assembled units may be carried to an enlarging, extruding, or thread rolling mechanism as shown in said Hanneman patent.

The assembly mechanism 4 may be of any suitable construction receiving a screw element at the lower end of the chute 6, moving downwardly to telescope the element into a washer and position it at the upper end of the chute 12 and then releasing the element for conveyance with the washer along the chute 12. Preferably this assembly mechanism is of the construction disclosed in the application of Walter M. Hanneman, Serial No. 344,359, filed July 8, 1940. Briefly stated, this assembly mechanism comprises a pair of screw receiving jaw members 18 fulcrumed on a hollow slide bar or sleeve 20 slidable in a tubular guide 22. The guide 22 carries a sleeve 24 having a bevelled inner surface 26 causing a desired opening movement of the jaw members as they approach their upper limit of movement and also carries an abutment or collar 28 causing a desired opening movement of the jaw members as they approach their lower limit of movement. A slide rod 30 for engaging the head of a screw clamped in the jaw members is slidably mounted in the bar or sleeve 20 and is operated by a lever 32. As the slide rod 30 moves downwardly it engages the head of the screw element and causes the jaw members holding the screw element to move downwardly.

The tubular guide 22 is carried by a bracket 34 adjustably secured at its outer end to a base casting or support 36. The lever 32 is moved downwardly by a spring 38 secured at one end to the lever and at the other end to the bracket. Rotary cam 40 moves the lever upwardly and controls its downward movement. The cam operates upon the lever through a slide pin 42 mounted in the bracket 34 and engaging a set screw 44 carried by the lever.

Washers are conveyed or supplied to the assembly point, in the path of movement of screw elements carried by the jaw members 18, by a combined hopper and washer feed mechanism 46.

The washer hopper 48 which in detail may be of the construction disclosed in the application of William Stern, Serial No. 277,344, filed June 5, 1939, or the application of Ougljea Jules Poupitch, Serial No. 282,517, filed July 1, 1939, includes an inclined annular washer retaining wall member or shell 50. A portion of the shell 50 is cut away in the line of the guide chutes so that one vertical edge of the wall at the cut away portion abuts the outer surface of the guide bar 10 and the corresponding opposite edge of the cut away portion abuts the outer surface of the guide bar 16. The bottom wall of the hopper is formed by a washer feed disc or shiftable member 52 rotatably supported upon a stationary disc or ring 54. The disc 52 and its supporting plate or

ring 54 are inclined, preferably at the same angle as the guide chutes 6 and 12 and the common axis of the disc and plate or ring is coincident with the axis of the shell 50 and this common axis extends substantially at right angles to the parallel longitudinal edges or surfaces of the guide chutes 6 and 12.

The tubular shell 50 may be secured to a hollow generally cylindrical member or housing 56 as by interfitting with the rabbeted upper edge of the housing (Figure 3). The ring or plate 54 is supported upon the upper edge of the housing within the tubular shell 50 (as seen in Figure 3). The annular wall of the housing 56 and the ring or plate 54 are cut away so that they abut the upper ends of the guide bars 14 and 16 and extend along the outer surface of the guide bar 16.

The disc 52 is rotated, preferably intermittently, by any suitable operating mechanism 58 which may be of the construction disclosed in the above-mentioned application of Ougljea Jules Poupitch.

The disc 52 is provided with a plurality of angularly spaced outwardly opening peripheral recesses or notches 60 extending radially with respect to the axis of the disc. Washers dumped into the hopper accumulate in a mass in the lower portion of the hopper. The disc 52 is preferably rotated in a counterclockwise direction as seen in Figures 1, 5, 6 and 9 to carry the washers first in an upward direction out of the mass and then the washers, having been properly seated in the recesses, are carried outwardly of the hopper to the point of assembly and onto the bars of the guide chute 12 adjacent their upper ends. It should be noted that the ring or plate 54 extends beneath the washer receiving notches 60 of the disc so as to hold the washers in these notches as against downward movement and guide the washers onto the bars 14 and 16, the upper surface of the ring or plate 54 lying in a common plane with the upper surface of the bars 14 and 16. As the disc is rotated, washers properly seated in the recesses of the disc are carried along the ring or plate 54 and onto the guide bars 14 and 16 beneath the assembly mechanism 4. After the screw elements or blanks have been assembled with the washers, the continued rotation of the disc carries the assembled screws and washers downwardly along the guide bars 14 and 16 a short distance when the washers are extracted from the recesses of the disc by being confined against further angular movement due to the interfitting of the shank of the screw element between the guide bars. Thus as the disc rotates after the screws and washers have been assembled, the assembled units are caused to move along a path tangent to the circular path of movement of the centers of the recesses in the feed disc. In order to facilitate extraction or ejection of the washers from the feed disc by the bars of the guide chute 12, the rear defining edge of each recess is cut away or curved rearwardly as at 62 so that there will be no tendency for the washers to become jammed between the forward and rear edges of the recesses as they are being extracted or ejected therefrom. The rounding of these edges as at 62 serves an additional purpose as will later appear.

A lug 64 is secured to the disc adjacent each recess 60. Each lug is formed to provide a portion or lip 66 overlying the adjacent recess along one side, preferably the rear side of the recess. As shown in Figures 1 to 11, each lug is also

formed to provide a flat upper surface portion 68, forward bevelled or tapering faces 70, 72 and 74, and rear faces 76 and 78 extending substantially at right angles to the surface of the disc 52. The bevelled faces 70 and 72 cooperate to provide the lip or overhanging portion 66 and the forward portion of the face 70 is cut away or recessed along the edge 80 to reduce the area of the overhanging lip or portion 66.

It should be noted that the disc 52 is of a thickness substantially equal, although slightly greater, than the thickness of the main body portion 82 of each washer so that this main body portion of a washer may be received within a recess between the lip 66 and the surface of the ring or plate 54. While therefore there is a sufficient distance between the lip 66 and the surface of the ring or plate 54 to permit the main body portion 82 of the washer to pass into the recess beneath the lip, this distance is so nearly equal to the thickness of this main body portion 82 of the washer that upward movement of the washer out of the recess is prevented.

The rear edge or surface 76 of each lug 64 is spaced from the forward lip 66 of the next following lug a distance sufficient to permit the washer to be freely received therebetween while causing the center or center of gravity of the washer to be positioned above the recess between the lugs so that a washer received between the lugs tends by its own weight to become tilted as shown in Figure 7. The rotation of the disc and the inertia of the washer will then cause the washer to move into the recess between the lugs and to lie beneath the overhanging lip 66.

The lug faces 70, 72 and 74 which are bevelled or tapered downwardly in the direction of movement of the feed disc direct the washers to the position shown in Figure 6 wherein they rest between the rear edge or surface 76 of one lug and the lip 66 of the following lug and abut or rest against the annular wall member or shell 50 of the hopper. The tapered face 72 of each lug provides a wedge which prevents interlocking of a second washer with a washer in a recess beneath the lip 66 and also acts to cause the second washer to be released or separated from the selected washer as the latter moves under the lip into its proper seat in the recess. A face 72 having released or separated a second washer from the washer seated under the lip, the released washer will gravitate along the disc into an unoccupied recess or back into the mass at the lower portion of the hopper.

The lug faces 74 and 78 converge inwardly of the inner edge of the adjacent recess. The face 78 of one lug forms with the face 74 of the following lug an enlarged washer directing passage converging toward the recess between the lugs so as to cause a washer as it gravitates along the disc to pass to the position shown in Figure 6. The tapered forward lug faces 70, 72 and 74 cooperate with the lug faces 68, 76 and 78 to provide means tending to prevent crown type washers from bunching or piling up in the position shown in Figure 10 and acting to break up any such stack of washers that may be formed. Crown type washers have a tendency to become interlocked or pile up as shown in Figure 10 with the crown of one washer received in the depressed crown forming portion of another washer and to collect in a stack or stacks wherein the washers rest on their edge and pile up against the annular wall of the hopper. If such a stack of washers is formed, the rotation of the disc 52

5 and the inertia of the stacked washers cause the washers to move over the lugs as in Figure 11 and due to the formation of the lug faces, the stack is broken up and the washers separated so that they lie flat on the surface of the feed disc. If a washer is or becomes positioned on the disc with its crown portion 84 extending downwardly instead of upwardly, the washer may reach the position shown in Figure 6, but it will not of course become tilted into the position shown in Figure 7. Hence it cannot pass under a lip 66 and therefore at some time before it reaches the assembly mechanism, will gravitate along the disc and strike some lug or other member which causes it to be turned into the proper position on the disc or it will be returned to the mass of washers in the lower part of the hopper. The rear edges 76 and 78 of the lugs, since they extend substantially at right angles to the face of the disc and are not bevelled or tapered in a vertical direction, prevent any loose washers which may be carried to the top portion of the hopper from rolling on edge or sliding flatwise over the lugs and out of the hopper through the cut away wall portion of the hopper shell.

Each lug extends to the periphery of the disc so that it will terminate in close juxtaposition to the annular wall or shell of the hopper and thereby carry the washers along the wall of the hopper as in Figure 11 and prevent their accumulation against this wall.

35 The lugs are provided with outwardly opening recesses 86 extending inwardly from the periphery of the disc to permit inward movement of the finger 88 of a washer detector 90 which may be of the construction disclosed in the Han- neman, Stern, or Poupitch applications above-mentioned. It suffices to observe that it comprises the finger 88 which is positioned to engage the rim of a washer at the assembly point, but if no washer is in a recess of the disc at the assembly point, the finger projects into the recess and is interposed as an abutment in the path of a screw carried by the assembly mechanism so that downward movement or operation of the assembly mechanism under the action of the spring 88 is prevented. The washer detector finger therefore prevents actuation of the assembly mechanism when there is no washer in position at the assembly point and thereby prevents feeding of a washerless screw blank to the guide chute 12. The recess 86 provides a clearance space for this washer detector. The rounded, rear, outer edge 62 of each recess also provides a cam surface engaging the finger 88 and returning it to its outer position as the disc rotates.

60 The washer feed disc 52 is also provided with a plurality of angularly spaced bars or rib forming portions 91 extending tangentially from a common imaginary circle to points of merger with equally spaced ones of the lugs 60 and 64. Each bar 91 is formed to provide a forward face 92 extending substantially at right angles to the surface of the disc and a bevelled face 94 tapering downwardly in a direction opposite to the direction of rotation of the disc. The bars 91 divide the surface of the disc into a plurality of sectors or sections each including a plurality of washer receiving recesses and interposed lugs 64. The abrupt face 92 of each bar prevents the washers from sliding on their flat faces from one sector to another during the time that the washers are being moved from the lower part of the hopper to the upper part of the hopper in order

that the washers may have a greater opportunity to become properly positioned for seating in recesses in the disc, and become seated in such recesses. The bevelled faces 94 of these bars 91 permit washers to slide downwardly of the disc as they pass beyond the highest point of the hopper so that they will be readily returned to the mass without interfering with the assembly operation and at the same time increase the possibility of their becoming seated in a recess from which a washer assembled with a screw element has just been extracted. In other words, the bars 91, by reason of their disposition and configuration, serve to so distribute the washers as to increase the opportunity for the washers to become seated in the recesses and thereby insure that each recess, by the time it reaches the assembly point, will have a washer seated properly therein.

In the form shown in Figures 12 to 14, advantage is taken of the difference in form between a flat internal tooth lock washer and a crown type washer to simplify the shape or construction of the washer directing lugs. As shown in this embodiment, the disc 52 is provided between each recess 60 with a lug 96 which is relatively thinner than the corresponding lug 64 of the embodiment shown in Figures 1 to 11. The lug 96 is formed to provide a flat upper surface 98, forward abrupt faces 100 to 102, rear abrupt faces 104 and 106 and outer abrupt face 108, the abrupt faces extending substantially at right angles to the surface of the disc 52. The face 100 cooperates with the face 108 to form a lip or portion 110 overhanging the recess along the rear side thereof. The lip 110 corresponds to the lip 66 of the form shown in Figures 1 to 11. The face 104 of one lug 96 is spaced from the forward face 100 of the following lug a distance sufficient to accommodate a washer therebetween, while at the same time to cause the center of gravity of the washer to be positioned over the recess so that the washer will be tilted and due to its inertia slide into the recess as the disc rotates and thereby to be positioned under the lip 110. The faces 106 and 102 of adjacent lugs diverge inwardly of the recesses so as to form an enlarged throat or washer directing passage for causing the washers to assume the position between the faces 104 and 100 of the adjacent lugs. It should be noted that the lug 96 terminates in its face 108 inwardly of the periphery of the disc 52, for unlike the crown type washers, these flat washers do not tend to stack up or stand on edge along the hopper wall. This termination of the lugs 96 inwardly of the periphery of the disc provides a clearance space for inward movement of the washer detector 90.

In the forms shown in Figures 15 and 16 the rotary disc or feed member is adapted for feeding oddly shaped washers, particularly crown type washers.

As shown in Figure 15, the main body portion of the crown type washer 110 has opposed rounded end edges 112 and opposed flat side edges 114. To accommodate this odd-shaped washer, the feed disc 116 is provided with angularly spaced outwardly opening peripheral recesses 118 having a longer axis extending radially of the disc, the recess being shaped to conform to the shape of the washers. Washer directing and retaining lugs 120 are secured between the recesses. Advantage is taken of the fact that the washers are to be seated with their flat edges extending in a generally radial direc-

tion to simplify the construction of these lugs. Thus these lugs 120 are formed to provide tapering faces 122 and 124 and abrupt faces 126 and 128, the faces 126 and 128 extending substantially at right angles to the surface of the disc and the faces 124 and 128 converging inwardly of the disc recesses. Since these crown type washers tend to pile up and stand on edge against or along the hopper wall, the face 122 of each lug is extended to the periphery of the disc and the lug is provided with a recess similar to the recess 86 to provide a clearance space for the washer detector finger 88. It should be observed that the face 126 of each lug is inclined at an outwardly diverging angle to the generally radial forward flat edge of the following recess 118 so as to cooperate with the faces 122 and 124 in causing the washer to be positioned with its flat edges extending radially rather than circumferentially relative to the disc and to cause the center or center of gravity of the washer to be positioned over the recess and hence become tilted and move under the lip or overhanging portion 130. The face 124 cooperates with the faces 128 and 126 of the preceding lug to direct the washers into the space between the lip and the face 126 of said preceding lug with the flat edges of the washer directed in a generally radial direction. It should be noted that the recessed flat edge 132 of each lug 120 extends in the same generally vertical plane with the rear flat edge of the washer receiving recess 118 so that the rear flat edge of a washer moving into the recess will not catch or jam on the surface 35 of the disc at the rear edge of the recess.

In some cases it may be found more convenient for various reasons to feed the odd-shaped, crown type, washers 110 with their longer flat sides 112 extending generally circumferentially or chordally of the disc as seen in Figure 16. For example, because of the shape or dimensions of the odd-shaped washer, it may be found convenient to feed the washers as shown in Figure 16, or again it may be desired to have the washers positioned with their flat sides extending lengthwise of the feed chute 12 when positioned at the assembly point. Again, with certain size washers, it may be found that the washers may be more readily extracted from the disc recesses if the washers are positioned as shown in Figure 16. In this form of the invention, the washer receiving recesses 134 of the disc 136 each have an inner flat edge 138, opposed rounded edge portions 140 conforming to the rounded edges 114 of the washer and merging into flat edge portions 142. The flat edge portion 142 merges into the outer curved edge 144 facilitating the withdrawal movements of the washers from the recesses after they have been assembled with the screw elements and providing a cam edge which as the disc rotates engages and moves the washer detector finger outwardly if a washer is not seated in the recess.

In view of the fact that the washers are to be seated with their rounded edges engaging the opposed forward and rear edges of the recesses, the washer directing and retaining lugs 146 are identical in construction with the washer detecting and retaining lugs 64 of the form shown in Figures 1 to 11 and perform their functions in a similar manner.

It should be noted that in respect to each form of the invention shown in the present application, the lip or overhanging portion of each lug overlies its associated recess a distance approxi-

mately equal to the thickness of the main body portion of the washer to be assembled. If this lip extends over the recess a distance substantially less than the thickness of the washer, its effect in retaining the washer in the recess as against vertical movement or "jumping" out of the recess will be greatly diminished. If the lip is extended over the edge of the recess a distance substantially greater than the thickness of the washer, there is a tendency for the washer to jam underneath the lip without becoming seated in the recess.

It will be evident from the foregoing description that applicant has provided a machine or mechanism for assembling screws and washers, and more particularly a means for feeding washers to an assembly point.

The invention also provides for use in an assembly mechanism or the like a washer feed device including a shiftable washer feed member or disc and means for preventing the washers from piling up or bunching on the discs.

Applicant further provides in his invention a washer feed disc having a shiftable washer feed member or disc and means to cause the washers to be properly seated in predetermined individual positions on the shiftable washer feed member or disc for conveyance to a predetermined point and causing each of the washers to be positioned in a predetermined manner at said point.

The invention also provides means cooperating with a recessed washer feed disc or member to insure positioning of a single washer in each recess and its proper seating therein and to prevent interlocking of other washers with the washer so positioned or seated.

More particularly the invention provides in combination with a recessed washer feed disc or shiftable member means to prevent the washers from "jumping out" of the recesses as the disc or shiftable member is operated.

Applicant has also provided a washer feed device including a hopper receiving a mass of washers and a disc or shiftable member operating beneath the mass to receive washers therefrom, and means cooperating with the disc or member to insure the feeding of the received washers in individual succession and in predetermined position to a predetermined point.

The invention further provides in a device for feeding countersunk washers means tending to prevent the stacking of washers and acting if a stack is formed to separate the washers from the stack so that they may be properly fed.

The invention also provides a device for feeding internal tooth lock washers from a mass in individual succession to a mechanism for assembling such washers with screws to produce a unit assembly of an internal tooth lock washer and a screw.

Applicant has further provided a device or mechanism for feeding or conveying internal tooth lock washers, particularly such washers of the crown type, from a receptacle or hopper containing a random mass of such washers.

Changes may be made in the form, construction and arrangement of the parts without departing from the spirit of the invention or sacrificing any of its advantages, and the right is hereby reserved to make all such changes as fairly fall within the scope of the following claims.

The invention is hereby claimed as follows:

1. Washer feeding means comprising a shiftable feed plate receiving on its surface a supply

of washers to be fed and having outwardly opening edge recesses receiving washers from the surface of the plate, washer directing lugs upstanding from the surface of said plate between said recesses and each having a portion thereof projecting over an adjacent recess to hold a washer in the recess.

2. Washer feeding means comprising a rotary disc receiving on its surface a supply of washers to be fed and having angularly spaced outwardly opening peripheral recesses receiving washers from the supply on the surface of the disc, washer directing lugs upstanding from the surface of said disc between said recesses and each having a portion thereof projecting over an adjacent recess to hold the washer in the recess during rotation of the disc.

3. Washer feeding means comprising a hopper having an inclined bottom wall section, said bottom wall section comprising a rotary disc projecting from the hopper for carrying washers out of the hopper, said rotary disc having a plurality of angularly spaced outwardly opening peripheral recesses into which the washers in the hopper gravitate, and a plurality of lugs upstanding from the surface of the disc and each having a portion projecting over an adjacent recess from the rear edge thereof to prevent the washers from jumping out of the recesses as the disc rotates.

4. Washer feeding means comprising an inclined disc receiving on its surface a supply of washers to be fed and having a plurality of angularly spaced outwardly opening peripheral recesses into which the washers gravitate from the surface of the disc, washer directing lugs upstanding from the surface of the disc between said recesses and having opposed upstanding faces converging outwardly to form a flaring passage directing the washers toward the recesses, each of said lugs having a portion projecting over the adjacent recess from the rear edge thereof to prevent washers from jumping out of the recesses as the disc is rotated.

5. Washer feeding means comprising an inclined disc receiving on its surface a supply of washers to be fed and having a plurality of angularly spaced outwardly opening peripheral recesses into which the washers gravitate from the surface of the disc, washer directing lugs upstanding from the surface of the disc between said recesses and having opposed upstanding faces converging outwardly to form a flaring passage directing the washers toward the recesses, each of said lugs having a portion projecting over the adjacent recess from the rear edge thereof to prevent washers from jumping out of the recesses as the disc is rotated, the rear faces of the lugs being spaced from the forward edges of the following recesses sufficiently to accommodate washers between adjacent lugs with their centers of gravity over the recesses whereby as the disc rotates, the washers become tilted and move into the recesses under the projecting portions of said lugs.

6. Washer feeding means comprising a rotary disc receiving on its surface a supply of washers to be fed and having outwardly opening peripheral recesses into which the washers move as the disc rotates, lugs upstanding from the surface of said disc between said recesses and each having its forward edge projecting over the adjacent recess to hold a washer in said recess, the forward face of each lug being bevelled upwardly and rearwardly from the surface of the disc.

7. Washer feeding means comprising a rotary disc receiving on its surface a supply of washers to be fed and having outwardly opening peripheral recesses into which the washers move as the disc rotates, lugs upstanding from the surface of said disc between said recesses and each having its forward edge projecting over the adjacent recess to hold a washer in said recess, the forward face of each lug being bevelled upwardly and rearwardly from the surface of the disc, the rear faces of the lugs being shaped to provide shoulders preventing washers lying flat on the surface of the disc from passing over the lugs in the direction of rotation of the disc.

8. Washer feeding means comprising a rotary disc receiving on its surface a supply of washers to be fed and having outwardly opening peripheral recesses into which the washers move as the disc rotates, lugs upstanding from the surface of said disc between said recesses and each having its forward edge projecting over the adjacent recess to hold a washer in said recess, the forward face of each lug being bevelled upwardly and rearwardly from the surface of the disc, said lugs having opposite upstanding face portions converging inwardly of the disc to form between adjacent lugs a flaring throat directing washers in the spaces between adjacent lugs.

9. Washer feeding means comprising a rotary disc receiving on its surface a supply of washers to be fed and having angularly spaced outwardly opening peripheral recesses receiving washers from the supply on the surface of the disc, washer directing lugs upstanding from the surface of said disc between said recesses and each having a portion thereof projecting over an adjacent recess to hold the washer in the recess during rotation of the disc, and angularly spaced ribs projecting upwardly from the surface of the disc and extending to spaced ones of said lugs to subdivide the surface of the disc into sections, the forward faces of said ribs being shaped to form ledges holding the washers lying on the surface of the disc against rearward movement from section to section as the disc rotates, said ribs also having rear faces bevelled from the surface of the disc to permit washers on the disc to pass forwardly from section to section as the disc rotates.

10. Means for feeding crown type washers comprising a washer hopper having an inclined rotary disc forming the bottom wall section thereof, said hopper having an annular upstanding wall portion with an opening therein through which the disc projects to carry washers out of the hopper to a discharge point, said disc having a plurality of angularly spaced recesses of a size to receive the main body portion of the crown washers with the crowns of the washers extending upwardly, lugs between said recesses and having portions forming lips projecting over the edges of adjacent recesses to prevent washers with their crowns extending downwardly from becoming seated in the recesses.

11. Means for feeding crown type washers comprising a washer hopper having an inclined rotary disc forming the bottom wall section thereof, said hopper having an annular upstanding wall portion with an opening therein through which the disc projects to carry washers out of the hopper to a discharge point, said disc having a plurality of angularly spaced recesses of a size to receive the main body portion of the crown washers with the crowns of the washers extending upwardly, lugs between the recesses, each lug having a portion forming a lip extending over an

adjacent recess and each lug having an opposite face portion spaced from the next adjacent recess sufficiently to cause a washer to be positioned between adjacent lugs with its center of gravity over the recess between the lugs to cause a washer with its crown extending upwardly to become tilted and to move into the recess under the lip of an adjacent lug, the lip forming portions of the lugs preventing washers with their crowns extending upwardly from becoming seated in the recess.

12. Means for feeding washers having opposed flat sides, said means comprising a rotary disc having a plurality of outwardly opening peripheral recesses for receiving washers from a mass on the surface of a disc, said recesses having opposed flat sides extending generally radially of the disc, lugs between the recesses and upstanding from the surface of the disc, said lugs each having an edge coincident with the edge of an adjacent recess and a portion forming a lip projecting from said edge of the recess over the recess to hold the washer in the recess and each lug having an opposite upstanding face portion spaced from the edge of an adjacent recess sufficiently to cause a washer to become tilted and move into the recess under the lip forming portion of the adjacent lug with the flat sides of the washer extending in the same direction as the flat sides of the recess.

13. Means for feeding washers having opposed flat sides, said means comprising a rotary disc having a plurality of outwardly opening peripheral recesses for receiving washers from a mass on the surface of a disc, said recesses having opposed flat sides extending generally radially of the disc, lugs between the recesses and upstanding from the surface of the disc, said lugs each having an edge coincident with the edge of an adjacent recess and a portion forming a lip projecting from said edge of the recess over the recess to hold the washer in the recess and each lug having an opposite upstanding face portion spaced from the edge of an adjacent recess sufficiently to cause a washer to become tilted and move into the recess under the lip forming portion of the adjacent lug with the flat sides of the washer extending in the same direction as the flat sides of the recess, the upper faces of the lugs being tapered upwardly from the lip forming edge portion of each lug to the opposed face portion of each lug.

14. Means for feeding washers having opposed flat sides, said means comprising a rotary disc receiving on its surface a supply of washers to be fed and having a plurality of outwardly opening peripheral recesses, the bottom wall of each recess extending chordally of the disc and being flat for engagement with one of the opposed flat sides of the washer, lugs between recesses and upstanding from the surface of the disc, adjacent lugs having opposed face portions of which one face portion forms a ledge positioning the washer with its center of gravity over the recess between the lugs and the other face portion is bevelled upwardly away from the adjacent edge of the recess to position the washer against the opposed face portion of the adjacent lug with one flat side extending chordally of the disc and in proper position for movement into the recess, the bevelled face portion of the lug projecting over the adjacent recess to provide a lip holding the washer in the recess.

15. In a mechanism for assembling screw and washer elements, washer feed means comprising

a shiftable feed plate receiving on its surface a supply of washers to be fed and having outwardly opening edge recesses receiving washers from the surface of the plate, lugs upstanding from the surface of said plate between the recesses and each having a portion thereof projecting over an adjacent recess to hold the washer in the recess, means for shifting said plate to carry

the washers in the recesses successively to the assembly point, and the recesses in said plate being adapted to release the washer for movement outwardly relative to the feed plate to withdraw the washer from beneath the overhanging portion of its holding lug as the plate carries the washers past the assembly point.

CHARLES J. IRWIN.

CERTIFICATE OF CORRECTION.

Patent No. 2,273,782.

February 17, 1942.

CHARLES J. IRWIN.

It is hereby certified that error appears in the printed specification of the above numbered patent requiring correction as follows: Page 2, first column, line 44, after "downwardly" insert --therewith--; and that the said Letters Patent should be read with this correction therein that the same may conform to the record of the case in the Patent Office.

Signed and sealed this 30th day of June, A. D. 1942.

(Seal)

Henry Van Arsdale,
Acting Commissioner of Patents.
